UNITED STATES PATENT OFFICE.

OSCAR S. FITZSIMONS, OF WATERBURY, CONNECTICUT, ASSIGNOR TO THE NOVELTY MANUFACTURING COMPANY, OF WATERBURY, CONNECTICUT, A CORPORATION OF CONNECTICUT.

FLAG-HOLDER ATTACHMENT FOR AUTOMOBILE-RADIATORS, &c.

1,022,360.

Specification of Letters Patent.

Patented Apr. 2, 1912.

Application filed July 6, 1910. Serial No. 570,541.

To all whom it may concern:

Be it known that I, OSCAR S. FITZSIMONS, a citizen of the United States, residing at Waterbury, in the county of New Haven and State of Connecticut, have invented certain new and useful Improvements in Flag-Holder Attachments for Automobile-Radiators, &c., of which the following is a specification.

10 My invention relates particularly to a device for supporting or holding a flag or pennant.

Small flags or pennants of various designs and bearing various insignia are often carried by motor vehicles either for purely ornamental purposes or to indicate membership in some organization, etc. By reason of the speed that the cars travel and of the uses to which the devices are subjected difficulty is often encountered in that the flag or pennant becomes furled or otherwise twisted and deranged.

It is my object to avoid this difficulty and at the same time provide a simple, inexpensive attachment which can be readily attached to a radiator cap or detached therefrom and to which a flag may be quickly attached or detached. By this means flags or pennants may be readily substituted, one for the other, when desired.

The preferred form of the invention is shown in the accompanying single sheet of drawings and the details of which will be readily understood from the following specification.

Figure 1, is a vertical projection of the attachment of my invention showing the flag flying. Fig. 2, is a vertical projection showing the parts of the attachment separated. Fig. 3, is a perspective view of a part of a motor vehicle or automobile with my attachment. Fig. 4, is a horizontal section showing the method of supporting the flag.

The term "flag" will be used throughout hereafter and in the claims to designate any type or design of flag or pennant or similar device.

A motor vehicle is indicated by the reference numeral 1 and has a radiator cap 2 on which is mounted my invention with a flag 3 on the post 4. On the post 4 is supported a wire frame or holder having a vertical portion 5 and terminating in loops or eyes 6 and 7 at the top and bottom respectively.

These loops encircle the post 4 and the bottom loop rests upon the collar 8. The lower part of the post 4 is slightly smaller in diameter than the upper portion and is screw-threaded at 9, a shoulder 10 being thus afforded between the screw-threaded portion and the main portion. The base 11 surrounds the screw-threaded end 9, the post being drawn down and attached to the radiator cap 2 by means of the two nuts 12 and 13, the shoulder 10 resting upon the upper surface of the base 11. By this means the device may be securely attached to the radiator cap. At the upper end of the post is a knob 14 having a screw-threaded portion 15 which engages in a screw-threaded recess or socket 16 in the upper end of the post 4. A flange 17 projects outwardly and has substantially the same diameter as the loop 6. In this way when the flag holder is mounted upon the post 4 the shank 15 of the knob 14 may be screwed down into the socket 16 so that the flange 17 will hold the loop 6 in place. While the wire holder is thus safely held it is left free to rotate upon the post 4 so as to prevent the flag 3 from being wound or furled upon the post.

When it is desired to remove the flag the knob at the top is unscrewed and the wire holder slipped off of the top of the post. The same flag or another may be readily put in place when desired.

What I claim is:—

1. An attachment for an automobile radiator or the like comprising a post having a base and a clamping device and a threaded recess at the upper end, a flag carrying holder revolubly mounted upon said post and a removable knob having a threaded stem coacting with said threaded recess for detachably holding the holder in place. 95

2. As an article of manufacture, an attachment of the character described comprising a post screw-threaded at its lower end, a base member surrounding the screw-threaded portion, a nut for securing said base member to said post and a second nut for clamping said post and base member to a support, a flag-carrying holder mounted upon and revoluble about said post above said base member and a knob removably engaging the upper end of said post for detachably holding said holder in place. 105

3. As an article of manufacture, an at-

2
tachment of the character described comprising a post, a base member secured on the lower end of said post, means for securing said post to a support, a collar loosely mounted on said post above said base member, a flag-carrying holder revolvably mounted on said post and resting on said collar and a knob detachably engaging the upper end of said post for holding the flag-carrying holder removably in place.

4. As an article of manufacture, an attachment of the character described comprising a post, a flag-carrying holder revolvably mounted upon said post, a support

on said post for supporting said holder, means for readily and detachably securing said post upon a suitable supporting device and a knob detachably secured to the upper end of said post above said flag-carrying holder for detachably securing said holder on said post, said holder being directly supported laterally on said post independently of said knob.

OSCAR S. FITZSIMONS.
